UNITED STATES PATENT OFFICE.

DANIEL WOODHEAD, OF EVANSTON, ILLINOIS.

MOUNTING FOR TRANSLATING DEVICES.

1,269,356.

Specification of Letters Patent. Patented June 11, 1918.

Application filed June 4, 1917. Serial No. 172,592.

To all whom it may concern:

Be it known that I, DANIEL WOODHEAD, a citizen of the United States, residing at Evanston, in the county of Cook and State 5 of Illinois, have invented a certain new and useful Improvement in Mountings for Translating Devices, of which the following is a specification.

My invention relates to mountings for 10 electric translating devices and is particularly applicable to fan mountings used in passenger car construction. In some respects the invention is related to the one shown in my companion application filed 15 on the 28 day of May, 1917, Ser. No. 171,354. In that application means are described for mounting a fan in such manner that it may be used in either one of two adjacent sections. The same is true in the present case, 20 but in the present case different means are employed. The underlying object of the present invention is to provide mountings whereby the fan or other electric translating device may be made effective in either 25 section and the mountings will render the sections completely private. One of the specific objects of the invention is to provide a pivoted bracket for supporting the fan, said bracket having side walls each of which is 30 adapted to form a portion of the partition when the fan is in operation. Another specific object is to provide means for housing the fan and at the same time permitting it to be adjusted so that it may direct the current of air in different directions as may be desired. Another object is to provide a friction device for yieldingly holding the fan at whatever inclination it is adjusted to. Other detailed objects will become apparent 35 as the description proceeds.

I accomplish my objects by the construction shown in the accompanying drawings, in which:

Figure 1 is a face view of a partition between two adjacent sections and shows the fan and its mountings in position.

Fig. 2 is a plan section on the line 2—2, Fig. 1.

Fig. 3 is a plan section showing two adjacent berths. The berths are shown to be made up, and the fans in proper acting position.

Fig. 4 is a plan section showing the fan and its mountings and associated parts. The plane of section is indicated by the line 4—4, Fig. 5.

Fig. 5 is a side elevation looking at the face of the partition and showing the fan bracket, housing, and locking device.

Fig. 6 is a sectional elevation on the line 60 6—6, Fig. 4.

Fig. 7 is a detail side view of part of the locking mechanism for preventing rotation of the fan supporting bracket.

Similar numerals refer to similar parts 65 throughout the several views.

As this invention is especially useful in sleeping cars, I have chosen to illustrate it in connection with a sleeping car of typical construction. For the present purpose it 70 will be unnecessary to describe the construction of the car further than to say that it has an outer shell 1 and inner shell 2 at the roof and upper part of the side. The sections are separated by partitions of which 75 the part 3 is stationary and the part 4 is removable. The removable part 4, usually termed the "head board," will ordinarily be in position only during the night time when the berths are made up.

In the present instance, I have shown the fan in a position to ventilate the upper berth. The berth itself, 5 is hinged to the side of the car as usual, and when lowered is suspended by chains or cables 6.

The fan blades 8 are mounted upon a motor shaft 9. The frame 10 of the motor has trunnions 11 journaled in bearings 12, screwed or otherwise fastened to the walls 13 of the supporting bracket. Said bracket 80 has trunnions 14, 15, located top and bottom as best shown in Fig. 6. These form a vertical axis for the fan bracket 13. They are located in the plane of the partition 3 and at the juncture of the two side walls 13, of 95 the bracket. The partition 3 has an opening 16 in it of the same size and shape as the wall 13. Consequently, when the bracket is in one acting position, one of the walls 13 forms a closure for the opening 16 and when 100 the bracket is rotated 90 degrees, the other wall 13 forms a closure for said opening.

Automatic locking means are provided for holding the fan bracket in one position or the other when the berths are made up. 105 In the form shown, a socket 18 is formed in the edge of each of the walls 13 as best shown in Figs. 2 and 4. The locking rod 19 is horizontally slidable in the fixed portion 3 of the partition, being mounted in a tube 110 20. The sockets 18 are in position to register with said locking rod and when the

end of the rod enters the socket, the bracket will be locked against rotation. Said rod is normally held in non-acting position by a spring 22 mounted in tube 20, as best shown in Figs. 2 and 5. A head 23 is formed at the outer end of said rod in position to be engaged by the stud 24, formed on the inner edge of the removable portion 4 of the partition. It will thus be seen that when the headboard is in place, it will cause the motor bracket to be locked against rotation and there is no way to unlock the bracket so long as the headboard remains in place. In order to hold the motor bracket locked during the daytime when the headboard is absent, a slot 26 is formed in the side of tube 20 as best shown in Fig. 7. A pin 27 is fastened to the locking rod and projects out through slot 26 so that the rod may be manipulated by hand. A notch 28 is formed at one side of the inner end of slot 26, and this retains pin 27 and holds the rod locked.

The fan is supplied with electric energy through the supply conductors 30, best shown in Figs. 4 and 6. These are led from the outside of wall 2 through a duct 31 thence up through the trunnion 15, which is hollow, thence through the duct 32 formed in the motor bracket in line with the axis of rotation thereof.

The motor frame and its supporting bearings are inclosed within a housing 35, which preferably assumes approximately the form of one-eighth of a sphere extending from one of the walls 13 to the other and centered coaxially with the trunnions 14, 15. Said housing covers all of the fan except the blades and a portion of the motor shaft. The motor shaft projects out through a vertical slot 36 in the housing, as best shown in Figs. 5 and 6. This permits a limited swing of the motor upon its trunnion and enables the operator to vary the angle of inclination of the shaft and thus vary the direction of the current of air delivered by the fan. It is desirable that no opportunity be afforded for the lubricating oil to escape from the housing, and I have arranged to prevent it by providing a shield 37 which slides on the inside of the housing and covers said slot. Said shield is spherical to conform to the configuration of this part of the housing and is held in close contact therewith by a spring 38, which encircles the motor shaft as best shown in Figs. 4 and 6. As a result, the fan may be swung up or down upon its trunnions to vary the direction of the air blast, and when thus adjusted the friction induced by the spring 38 between the shield 37 and housing 35 will yieldingly hold the fan in the position in which it is set. In the preferred construction the fan and motor are practically balanced upon the trunnions 11, and hence no

great amount of friction is required to maintain the fan in the position to which it is adjusted.

The operation will now be readily understood. In sleeping cars, the berths are almost invariably made up in such manner that the head of the occupant will be nearest to the locomotive. It is desirable that the fan always be at the foot of the occupant. Hence when the porter prepares to make up the berth, he positions the fan brackets in the manner illustrated in Fig. 3, employing for a given section the fan located at the foot of that section. As soon as the headboard 4 is in place, it will lock the bracket 30 walls 13 in position, and they will then remain fixed until the headboard is removed. The motor and fan may then be adjusted relatively to the supporting bracket and the occupant may obtain any angle of delivery 35 desired. As for the supply conductors, no sliding contacts are required for they lead up through the axial point of the bracket and as the bracket is confined in its movements to about 90 degrees, the conductors 90 cannot be excessively twisted and hence cannot be harmed by the movement of the bracket.

As a result of this invention it becomes practical to ventilate each individual berth, 95 and to always have the fan at the foot of the berth without providing a greater number of fans (except for the end berths), than there are berths in the car. Furthermore, the space occupied is reduced to a minimum, 100 the appearance is neat, and the privacy of the berths is in no way decreased.

I claim—

1. A passenger car having sections separated by partitions, each partition having an opening and being composed of a fixed and a movable part, an electric translating device, a pivotally mounted support therefor having side walls arranged at approximately right angles to each other, said walls each being adapted to form a closure for said opening, and locking means operated by the movable part of the partition for locking said support against rotation.

2. A passenger car having sections separated by partitions, each partition having an opening, an electric fan, a fan-supporting bracket having two walls arranged approximately at right angles to each other with the fan between them, each of said walls being adapted to form a closure for the opening in the partition, and a pair of trunnions for pivotally supporting said bracket to permit it to rotate about a vertical axis, the trunnions being located in the plane of the partition and at the intersection of the walls of the bracket, one of said trunnions being hollow to permit the supply conductors to be led through it to the fan.

3. A passenger car having sections sepa-

rated by partitions, an electric fan having a motor, fan shaft and blades, and a support for the fan pivotally mounted upon a vertical axis in the plane of the partition, the fan being pivotally mounted upon said support and being free to swing in a vertical direction.

4. A passenger car having sections separated by partitions, an electric fan having a motor, fan shaft, and blades, a support for the fan pivotally mounted upon an axis in the plane of the partition, the fan being pivotally mounted upon said support, and a housing for the motor having a slot for accommodating the fan shaft, said slot extending in a plane perpendicular to the motor pivot.

5. A passenger car having sections separated by partitions, an electric fan having a motor, fan shaft and blades, a support for the fan pivotally mounted upon an axis in the plane of the partition, the fan being pivotally mounted upon said support, a housing for the motor, said housing having a spherical portion with a slot in it for accommodating the fan shaft, said slot extending in a plane perpendicular to the fan pivot, and a shield encircling the fan shaft and lying adjacent to the housing for closing the slot therein.

6. A passenger car having sections separated by partitions, an electric fan having a motor, fan shaft and blades, a support for the fan pivotally mounted upon an axis in the plane of the partition, the fan being pivotally mounted upon said support, a housing for the motor, said housing having a spherical portion with a slot in it for accommodating the fan shaft, said slot extending in a plane perpendicular to the fan pivot, a shield encircling the fan shaft and lying adjacent to the inside of the housing to form a closure for the slot, and a spring for forcing the shield toward the housing.

45 7. A passenger car having sections separated by partitions, each partition having an opening, an electric fan having a motor, fan shaft and fan blades, a bracket having two walls arranged approximately at right

angles to each other and each adapted to form a closure for said opening, said bracket being pivotally supported so as to rotate about a vertical axis in the plane of partition, said walls being on opposite sides of the fan, pivot bearings arranged horizontally for supporting the motor upon the bracket, a housing extending from one wall to the other and passing in front of the motor, said housing having a spherical portion in front of the motor, and having an opening in it through which the fan shaft extends, the blades being in front of the housing and the motor behind it.

8. A passenger car having a ventilating fan comprising an electric motor, motor shaft and blades, a support for the motor, pivot bearings for said motor whereby the direction of delivery may be changed, a housing in front of said motor having a slot for accommodating the motor shaft, and a friction device bodily movable with the motor and rubbing upon said housing for yieldingly holding the motor in the position to which it is adjusted.

9. A passenger car having sections separated by partitions, each partition having an opening, an electric fan having a motor, fan shaft and fan blades, a bracket having two walls arranged approximately at right angles to each other and each adapted to form a closure for said opening, said bracket being pivotally supported so as to rotate about a vertical axis in the plane of partition, said walls being on opposite sides of the fan, pivot bearings arranged horizontally for supporting the motor upon the bracket, a housing extending from one wall to the other and passing in front of the motor, said housing having a spherical portion in front of the motor, and having a vertical slot for accommodating the fan shaft, and a spring pressed non-rotating friction member movable in unison with the shaft and engaging the housing to hold the shaft at any angle to which it is adjusted.

In witness whereof, I have hereunto subscribed my name.

DANIEL WOODHEAD.
